UNITED STATES PATENT OFFICE

RALPH DEANS, OF NEAR ATLANTA, GEORGIA

CORSAGE RETAINER

Application filed November 25, 1929. Serial No. 409,639.

This invention relates to a retainer expressly designed for attaching diversified forms of ornaments to wearing apparel, the same being especially useful for securing in 5 place bouquets, boutonnières, shoulder ornaments, and corsages.

The present day corsage which is generally fastened to the garment adjacent the shoulder of the wearer is in the nature of 10 an ornamental group of flowers or the like, whose stem portions are assembled and tied together to form what is generally referred to as the backbone.

In carrying the present invention into effect I have evolved and produced novel retainers whose common structural features serve to provide a simplified, economical and dependable retaining device which precludes many of the unsatisfactory results of the 20 bunglesome types of pins and analogous retainers now generally used in the trade.

My principal aim is to generally improve upon patented and marketed corsage retainers of this class by providing a structure 25 which is neat, such as to be practically concealed when in position, dependable and efficient in operation and use, and otherwise susceptible of fulfilling the requirements of an article of this class in a highly satisfactory 30 and practical manner.

In the present application, I have shown and will specifically describe the distinguishable embodiments of the invention which may be satisfactorily utilized for accomplishing the desired results. Generically stated, the retaining device comprises 35 lengthy backing means for the backbone of the corsage which is constructed to permit said backing means to be fastened to the 40 wearing apparel to afford a rigid and sturdy support for the complete corsage, this backing means having associated therewith, corsage embracing means which is practically imbedded in the back portion of the corsage, said means being such as to securely 45 hold the corsage in place without liability of crushing the stem or in any other manner developing ruinous results.

In the drawings:

50 Figure 1 is a perspective view of one em-

bodiment showing a cruciform backing member.

Figure 2 is a perspective view showing another form wherein the backing member is of general I-shaped configuration. 55

Figure 3 is a perspective view wherein the backing member is in the nature of an elongated safety pin.

Figure 4 is a view quite similar to Figure 3 with the smaller right angularly disposed safety pin loosely fastened to the backing member. 60

Attention is first invited to Figure 1 wherein it will be seen that the retainer comprises a cruciform backing member 5 of appropriate 65 proportions and material. It is preferably in the nature of a flat metal body on the back of which the elongated pin 6 is arranged. The pointed end of the pin is engaged with the complementary keeper 7 on the lower end 70 of the stem portion of the backing member.

The crossed portion of the backing member, designated at 8 is equipped with a relatively short, right angularly disposed pin 9 75 cooperable with the keeper 10. This pin 9 is adapted to embrace the backbone (not shown) of the corsage in an obvious manner.

In Figure 2, the reference character 11 designates the elongated backing member which is here shown as of I-shaped configuration. It includes the central stem portion 12 having cross heads 13 and 14 at its opposite ends. The elongated retaining pin 15 is disposed directly behind the backing member 11 80 and cooperable with the keeper 16. 85

The smaller right angular disposed pins 17 and 18 are mounted on the crossheads 13 and 14 respectively and cooperable with their complementary keepers 18, 19 and 20 respectively. 90

In Figure 3, the backing member is in the nature of an elongated safety pin generally designated by the reference character 21. Here I provide smaller pins 22 and 23, these being centrally soldered or otherwise rigidly mounted on the end portions of the main pin 21. 95

Referring now to Figure 4, it will be seen that the structure is quite similar to that just described in Figure 3. In Figure 4, the ref- 100

erence character 24 designates the elongated safety pin which constitutes the combined fastening means and backing means for attachment to the backbone of the corsage. This pin is provided at its opposite ends with coils 25 in which the eye 26 of the smaller pins 27 are mounted. This provides a comparatively flexible pin which better conforms to irregularities and yet provides the desired rigidity of attachment.

From the foregoing description and drawings, it will be seen that I have evolved and produced a simplified and economical type of corsage holder or retainer which is uniform in its retention action and susceptible of being securely fastened to the garment in a tidy manner.

It is submitted that in fastening a corsage it is desirable that it be fastened at at least two points and a reasonable distances from each other in order to remain in fixed position, and to avoid any tendency of the corsage being displaced by shifting body motion.

The present day corsage is generally of the shoulder type with none of the stems showing below the corsage. Hence the retainer must be of such a nature as to be easily placed in position without breaking the stems or the flowers and such as to be practically concealed so as not to destroy the beauty of the corsage.

The corsage embracing pin either encircles the backbone of the corsage or are passed through the same, and the larger pins is disposed in the garment in a substantially perpendicular manner, thus holding the corsage in an imposing and attractive position without liability of swinging while the body is in motion.

Taking into consideration the scanty attire generally worn with bouquets of this particular species, the features of concealing and firm attachment to a small area of the garment will be appreciated by persons skilled in the art to which the invention relates.

A careful consideration of the description in connection with the drawings will permit a clear understanding of the construction, attachment, and features and advantages to be had. Therefore, a more lengthy description is regarded as unnecessary.

Minor changes in shape, size and materials and rearrangement of elements coming within the field of invention claimed may be resorted to in actual practice if desired.

I claim:

In a corsage retainer of the class described, a multi-part structure including a backing member adapted to be disposed in intimate contact and alignment with the body of aggregated stems of the corsage, means carried by said backing member to maintain said body of aggregated stems in comparatively immovable intimate contact and alignment with said backing member, which means being characterized by the absence of rough and

sharp projecting edges having a tendency to make destructive contact with the stems or other parts of the corsage.

In testimony whereof I affix my signature.

RALPH DEANS.
